UNITED STATES PATENT OFFICE.

HERI BOBST, OF LAUSANNE, SWITZERLAND, ASSIGNOR TO ETABLISSEMENTS MARINONI, SOCIÉTÉ ANONYME, OF PARIS, FRANCE, A CORPORATION OF FRANCE.

MECHANISM FOR THE MARGINING AND THE FEEDING OF SHEETS TO ROTARY MACHINES.

Application filed February 29, 1924. Serial No. 696,015.

To all whom it may concern:

Be it known that I, HENRI BOBST, a citizen of Switzerland, residing at Lausanne, Canton of Vaud, in the Confederation of Switzerland, have invented certain new and useful Improvements in Mechanism for the Margining and the Feeding of Sheets to Rotary Machines, of which the following is a specification.

10 The invention relates to a mechanism for the margining and the feeding of sheets to rotary machines for working the paper, card-board, and other sheet material and comprising a device for the introduction of 15 marginated sheets, and having rotary feeding members between which the sheet is made to pass in order to arrive at the marginating members, whereby at least one of said rotary members being capable of being displaced vertically with regard to the other.

The mechanism comprises members for periodically operating the marginating members and the feeding members, these latter at least separating them one from the other in order that a sheet is allowed at the marginating members and for stopping their rotation, in such a manner that the sheet is pinched between them during a stoppage of this movement, the feeding members being thereupon operated in such a way, that the sheet is being delivered to the entraining members of the working machine at a speed which essentially corresponds to their circumferential speed.

The attached drawing shows a working form of the invention given by way of example.

Fig. 1 is a plan view showing partially the working machine certain members being however not represented for the sake of more clearness.

Fig. 2 is a side elevation of said mechanism (side opposite to the drive).

45 Fig. 3 is a section along the line $a-a'$ of Fig. 1, showing the margining targets.

Fig. 4 is a section along the line $b-b'$ of Fig. 1, showing an air brake and the driving member of the shaping machine.

50 The Figs. 5, 6, 7 and 8 show the margining targets and the feeding mechanism in different working positions.

Fig. 9 represents a brake of the sheet entraining top roller.

Fig. 10 shows a cross-bar for blocking the feeding mechanism and

Fig. 11 refers to a detail of the air brake.

The sheets which are to be fed to the working machine are piled on to the table 1 (Fig. 3) against the margining targets 2 and against a lateral target not represented in the drawing. The placing of the sheets is effected by hand or automatically by means of the marginer.

Each of the fork shaped margining targets 2 is mounted on a slide 3 and may swing on an axle 4 and become fixed in a position determined by the screws 5 and 6 of a rod 7 connected to the slide 3. This latter may slide vertically within a support 8. A spring 9 aims at producing an upward movement of the slide 3 whilst a lever 10 keyed on a shaft 11 is provided for causing a downward movement of the guide or of the target 2 respectively. Bossages 12 of the support 8 are traversed by the shaft 11 and support a guide 13 serving as a rest to the sheet 14.

The support 8 may be laterally displaced. It is retained upon a cross-tree 15 by means of a head sliding within a groove 17. The cross-tree 15 is fixed to the members 18 and 19 of the shaping machine. When the target is laterally displaced the key of the lever 10 slides in a groove 20 of the shaft 11, the lever being entrained by the bossage 12 of the support 8.

The elevation and the intermittent descent of the target 2 is obtained by the shaft 11 rotating in the members 18 and 19. One of the ends of this shaft carries a double lever 21 (Figs. 2 and 10) whose lower portion does, owing to the springs 9, press constantly upon a lever 22 which pivots on a gudgeon 23 and carries a roller 24 rolling upon a cam 25 whose rotation produces an alternative motion of lever 22 from which it is transmitted to the shaft 11. The cams 25, 26 and 27 are keyed onto the wheel 28 running loosely on a gudgeon 29. The wheel 28 is rotated by the driving pulley 31 by the intermediary of a pinion 30 and of a shaft 32 (Figs. 1 and 2).

An axle 33 rigidly fixed to the members

18 and 19 supports the superior guides 34 of the sheets 14. Each guide 34 may be raised or lowered in accordance to the thickness of the sheets by means of the screws 35 and 36 which maintain said guide upon a support 37 sliding on the axle 33 (Figs. 3 and 8).

5 By unscrewing a screw 38 each guide 34 may be displaced simultaneously with the target 2 in order to retain the position shown in Fig. 8.

10 The lower roller 39 for feeding the sheets rotates freely in the members 18 and 19 and carries at one of its ends a pinion 40 operated by a toothed sector 41 (Fig. 1) carried by a shank of a bent lever turning loosely on a gudgeon 42. This same shank carries a roller 43 rolling on a cam 27 and the other shank is submitted to the action 15 of a spring 44 which tends to maintain the roller 43 in contact with the cam 27. The latter which is operated by the wheel 28 causes, by the intermediary of the sector 41, a periodical rotary motion of the 20 roller 39.

25 A pinion 56 mounted upon the roller 39 on the side of the drive, engages with a rack 57 sliding in a support 58 fixed on the cross-piece 15 (Fig. 4). The rack 57 is connected to a piston 59 sliding within a cylinder 60 fixed to the framing of the 30 shaping machine.

35 The lower portion of the cylinder 60 is provided with a valve 61 (Fig. 11) which has a hole 62 in its center which is partially closed by a ball 63 kept in position by a screw 64. The air passing through the opening left open by the ball 63 may escape through a lateral hole 65. The chamber 66 40 is communicating with the outside through the opening 67 and gives access to the air to the cylinder when the valve 61 is raised.

45 The shaft 45 turns freely in connecting-rods 46 and 47 and being kept in position by the grooves 48 and 49 of the members 18 and 19 carries the entraining rollers 50 coming periodically into contact with the roller 39. The entraining rollers 50 are 50 connected by means of a sleeve sliding on the shaft 45. The groove 51 between the rollers 50 allows the support 37 to take the rollers along so that these do follow the lateral displacement of the target 2 and of the guide 34 (Fig. 1).

55 By the intermediary of a roller 52 of the levers 53 and 54 which are simultaneously operated by a shaft 55 the cam 26 causes a periodical raising and lowering motion of the roller 45 by means of the connecting 60 rods 46 and 47 (Fig. 2).

65 A belt 68 fixed by one of its ends to the cross-tree 15 (Fig. 9) passes over the roller 45 whilst its other end is provided with a stretcher 69 entering a set screw 70 fixed to the member 19. The tension is regulated

in such a way that the roller 45 is braked when it is in its raised position and is free when in its lowered position.

70 The entraining rollers 71, 72 of the shaping machine are always rotating in the same direction when the machine is running and the bottom roller 71 carries on one of its ends a pinion 73 engaging with an intermediary wheel 74 operated by the gear 75 of shaping cylinder 76. This latter is 75 driven by the gear 77 mounted on shaft 32 (Fig. 4).

77 The top roller 72 is taken along by simple friction by the roller 71. The journals of the roller 72 traverse the members 18, 19 80 through two notches 78, 79 and may be raised by two hooks 80, 81 swinging upon the gudgeon 82, 83. By operating the hooks 80, 81 the roller 72 will be raised so that it will come out of contact with roller 71. 85

85 A crosshead 84 (Figs. 2 and 10) having two shanks 85, 86 and being operated by the knob 87 is turning freely in the frame 18. The nose 88 of the lever 21 operating the shaft 11 comes into contact with the shank 85 of the crosshead whilst the nose 89 of the connecting rod 46 comes into touch with the shank 86 of the crosshead. The shanks 85, 86 being arranged 90° one from the other it is possible by turning the knob 87 by 90° to bring the shank 85 into a horizontal position whereby the return of lever 21 and consequently the raising of the target 2 is prevented, whilst the shank 86 in its vertical position prevents the descent of the connecting rods 46, 47 and of the shaft 45 respectively. 95

100 The working manner of the mechanism is as follows:

105 The sheet 14 (Fig. 3) placed upon the table 1 is brought against the front targets 2 and a lateral target not visible in the drawing. The placing of the sheet may take place either by hand or by an automatic margining device. The front targets 110 are generally arranged two in number, however a larger number may be provided for. The lateral displacement along the cross-tree 15 allows to place them in a convenient distance according to the size of the 115 sheets. The displacement of the target 2 rendered possible owing to the screws 5 and 6 allows to introduce the sheets easily parallel to the rollers or slightly aslant in one direction or the other. The top guide 34 120 is displaced simultaneously with the target 2 for maintaining the position according to Fig. 8. The displacing of the guide 34 or its support 37 respectively causes equally the displacing of the entraining rollers 50 125 in such a manner that they always work in front of the target 2. The groove 51 between the rollers allows the guide 34 to bring down the sheets which might tend to raise and to lead them exactly to the tar- 130

get 2. The distance between the guides 13 and 34 is arranged but slightly superior than the thickness of the sheets so that the borders of the latter may not turn round or escape upwards or downwards.

Once the sheet is brought in place against the targets 2, the shaft 45 will descend under the action of the cam 26 until the rollers 50 press the sheet on to the roller 39 which 10 at this moment is at rest, the roller 54 of the sector 41 rolling at this instance upon a portion which is concentric to the axle of the cam 27. The position obtained is shown in Fig. 5. As soon as the sheet is 15 pressed between the two rollers, the roller 43 is brought in front of a slight cavity of the cam 27 whereby a very slight back motion of the sheet 14 is obtained whilst the targets 2 are being lowered under the action 20 of the levers 10 operated by the shaft 11, the lever 21 being raised under the action of the roller 24 rising upon a nose of the cam 25 (Fig. 6).

When the targets 2 are completely lowered, the cam 27 acts upon the sector 41 and causes a rotary motion of the roller 39 and thereby the advance of the sheet 14. The advance, beginning with zero is progressively accelerated and attains when the sheet 30 enters between the rollers 71 and 72 essentially the circumferential speed of these latter. This speed is obtained a few moments before the sheet penetrates between the rollers 71 and 72 and is maintained a few moments afterwards so as to avoid a sliding of the sheet. As soon as the sheet is gripped by the rollers 71, 72 the rollers will be raised, the sheet continues its way in the shaping machine being taken along by the 40 rollers 71 and 72 (Fig. 7).

The inertia acquired by the accelerated rotation of the roller 39 is absorbed by the air brake (Fig. 4). According to rotation of the roller 39 the piston 59 compresses air 45 in the cylinder 60 which finally absorbs the whole of the inertia. The efficacy of the brake may be increased or reduced by obturating by means of the ball 63 more or less the air channel 62 of the valve 61. 50 The return of the roller 39 in its initial position is effected slowly under the action of the spring 44 (Fig. 2). In order to not create a resistance, the vacuum produced by the ascending of the piston 59 raises the 55 valve 61 which thereupon gives entrance to the air into the cylinder 60. When the roller 39 is being returned, the sheet 14 slides freely upon the latter since the contact has been suppressed by the elevation of the rollers 50 (Fig. 7).

When the sheet 14 is advancing the rollers 50 and the shaft 45 have acquired a rotary speed corresponding to the feeding speed of the sheet. The setting at rest of the rollers 50 in their elevated position is effected

by the belt 68 (Fig. 9). Its tension is adjusted in such a way that the rollers 50 are set at rest when they come to pinch the new sheet on the roller 39. The descending of the shaft 45 slackens the belt so that the 70 shaft and the rollers may turn freely during the feeding of the sheet.

After the passage of the end of the sheet the targets 2 are raised under the action of the springs 9 for putting another 75 sheet in place.

There may occur cases when it is wished to introduce a sheet into the shaping machine without utilizing the mechanism of the targets 2 and of the feeding 80 roller 39. By turning the knob 87 by 90° the arm 85 stops the lever 21 and prevents the rise of the targets 2, besides the nose 89 of the connecting rod 46 may no longer descend since the arm 86 is now in a vertical position 85 and thus prevents the rollers 50 to descend upon the roller 39. This latter runs idle. The space between the guides 13 and 34 is continuously free so that the sheets may be introduced directly into the rollers 71 and 72 which are continuously taken along by the shaping machine.

By again turning the knob by 90° the motion of the targets 2 and the descending 95 of the rollers 50 is reestablished.

For adjusting the shaping machine a sheet may be slid up to the shaping apparatus whilst the machine is being stopped, by turning the knob 87 by 90° for causing the stoppage of the targets 2 and the rollers 50 and by raising the roller 72 by means of the hooks 80, 81.

The entraining rollers 71, 72 might be eliminated in order to allow to deliver the sheets directly to the taking along members of the working machine.

Having now described my invention and the manner in which it is to be performed, I declare that what I claim is:

1. A mechanism for margining and feeding the sheets to rotary machines for working the paper, the cardboard and other sheet-material, comprising, in combination, margining members, a device for the introduction of marginated sheets and presenting rotary feeding members between which the sheets are caused to pass in order to arrive at the margining members, at least one of said rotary members being adapted to become vertically adjusted with regard to the others, members for periodically operating the margining and the feeding members, these latter at least for the purpose of separating them one from the other in order to enable a sheet to arrive in front of the margining members and for stopping the rotation of the feeding members in such a manner that the sheet may be pinched during such a stoppage of rotation, a toothed sector to cause the rotation of one of the rotary mem- 110
115
120
125
130

bers producing the advance of the sheet, a braking device provided for suspending the motion of this rotary member when the toothed sector which operates it is made 5 to return, for the purpose of avoiding shocks in the working of the mechanism.

2. A mechanism for margining and feeding the sheets to rotary machines for working the paper, the cardboard and other sheet-material comprising, in combination, a device for the introduction of margined sheets and presenting rotary feeding members between which the sheets are caused to pass in order to arrive at margining members, 10 at least one of said rotary members being adapted to become vertically adjusted with regard to one another, members for periodically operating the margining and the feeding members, these latter at least 15 for the purpose of separating them one from the other in order to enable a sheet to arrive in front of the margining members and for stopping the rotation of the feeding members in such a manner that the sheet 20 may be pinched during such a stoppage of rotation, a toothed sector to cause the rotation of one of the rotary members producing the advance of the sheet, an air brake for suspending the motion of this rotary member 25 when the toothed sector is made to return, said air brake comprising a cylinder in which a piston is displaced, said piston having a valve for adjusting the speed of the displacement of the piston within said 30 cylinder.

3. A mechanism for margining and feeding the sheets to rotary machines for working the paper, the cardboard or other sheet-material comprising, in combination, a device 40 for the introduction of margined sheets and presenting rotary feeding members between which the sheet is made to pass in order to arrive at margining members, at least one of said rotary members being adapted to become vertically adjusted with regard to one another, members for periodically operating the margining and the feeding members, these latter at least for the purpose of separating them one from the other in order 45 to enable a sheet to arrive in front of the feeding members and for stopping the rotation of the feeding members in such a manner that the sheet may be pinched during such a stoppage of rotation, the feeding members being arranged one on top of the other, the bottom one being fixed while the top member is vertically displaceable, the bottom member being constituted by a shaft 50 carrying a roller and the top member by a shaft carrying at least two rollers adapted to bear upon the sheet to be taken along in order to move it, a guide being disposed between each pair of these rollers for depressing the sheets tending to rise, said guide 55 being adjustable in height according to the

thickness of the sheets, each margining member being provided with a guide of fixed height laterally displaceable for retaining the sheets which may tend to descend, the top guide and the rollers of the top guide 70 being transversely movable in order to arrange them opposite the lower guides and the margining members.

4. A mechanism for margining and feeding the sheets to rotary machines for working the paper, the card-board or other sheet-material comprising in combination a device for the introduction of margined sheets and presenting rotary feeding members between which the sheet is made to pass in order to 75 arrive at margining members, at least one of said rotary members being adapted to become vertically adjusted with regard to one another, members for periodically operating the margining and the feeding members, these latter at least for the purpose of separating them one from the other in order to enable a sheet to arrive in front of the margining members and for stopping the rotation of the feeding members in such 80 a manner that the sheet may be pinched during such a stoppage of rotation, members provided for giving the feeding members a motion in order to deliver the sheet to the entraining members of the machine at a speed essentially equal to their circumference speed, said members comprising a cam upon which a roller mounted on a bent lever is made to rest, said bent lever being submitted to the action of a spring which continually tends to make the roller to bear upon the cam, one of the legs of the lever carrying a toothed sector which engages with a pinion of the lower rotary feeding member. 85

5. A mechanism as claimed in claim 3 comprising means to brake the top shaft when it is out of engagement with a sheet in order to stop its motion. 90

6. A mechanism as claimed in claim 3 comprising a belt adapted to stop the rotation of the top shaft when the shaft is in its raised position while the latter is left free whilst being in its lower position. 105

7. A mechanism for margining and feeding the sheets to rotary machines for working the paper, the card-board or other sheet-material comprising in combination a device for the introduction of margined sheets and presenting rotary feeding members between which the sheet is made to pass in order to arrive at margining members, the top rotary member being adapted to become vertically adjusted with regard to the lower rotary member, members for periodically operating the margining and the feeding members, these latter at least for the purpose of separating them one from the other in order to enable a sheet to arrive in front of the margining members and for stopping the 110

120

125

130

rotation of the feeding members in such a manner that the sheet may be pinched during such a stoppage of rotation, the margining members being targets which are disposed in such a manner as to allow of their transversal displacement with regard to the direction of displacement of the sheets as well as of their displacement in the direction of that of the sheets, members adapted to stop the motion of the targets and the ascending and descending motion of the top rotary member, these members comprising a

shaft carrying two arms arranged in such a manner that when the mechanism is running and this shaft is given a movement about 90° the arms carried by it will lock the one of them the driving members of the targets and the other one the members controlling the ascending and descending motion of the upper rotary member. 15 20

In testimony whereof I have affixed my signature.

HENRI BOBST.
